UNITED STATES PATENT OFFICE.

EMIL JACOBSEN, OF NEW YORK, N. Y., ASSIGNOR, BY MESNE ASSIGNMENTS, TO AUTOMATIC ELECTRIC INC., OF CHICAGO, ILLINOIS, A CORPORATION OF DELAWARE.

SEMITAUTOMATIC TELEPHONE SYSTEM.

Application filed March 13, 1919, Serial No. 282,442. Renewed August 26, 1927.

My invention relates in general to a semi-automatic telephone system and more particularly to an improved method of extending calls in such a system. By extending a call is meant the operation performed by one party when called to extend the connection from the calling party to some other called station.

Among the features and objects of my invention are to provide means whereby when a connection is set up from a calling party through a main exchange to a branch exchange attendant, the attendant may then operate certain switches in the main exchange to extend the connection from the main exchange to another branch exchange without disconnecting the calling party from the extended connection.

The above results are accomplished by providing a special selector repeater in the main exchange which has access over two-way trunk lines to a branch exchange and which selector repeater may be operated in a certain manner by the attendant in the called branch exchange to extend a connection from the selector repeater through a line switch associated therewith to a selector and either to another called line in the main exchange or to another branch exchange. A system of this character is especially valuable where a company has two branch offices each equipped with a branch exchange. Now when a call comes into a branch exchange and it is found that the party desired or the information desired must be obtained from the other branch office, then the attendant at the first called branch can extend the connection to this second branch exchange without making it necessary for the calling party to hang up and call again.

Referring to the accompanying drawings, Fig. 1 shows the usual calling substation A and individual line switch C having access to selector switches such as D which selectors have access to selector repeaters E (Fig. 2) all of which equipment is in the main or central office. A line switch C' is associated with this selector repeater E (Fig. 2) which is used only for special calls.

The selector repeater E has access to a number of two way trunk lines extending to branch exchanges one of which trunk lines is shown extending to a branch exchange attendant's circuit F (Fig. 3) and through the

attendant's circuit to a connector H (Fig. 55 4) which has access to lines in this exchange. This two way trunk line may also be used for calls in the opposite direction in which case the line switch C³ is used to connect with the regular selectors in the main exchange. It will be understood that the line switches C, C' and C³ all have access to selector switches such as D (Fig. 1) for completing connections in the main exchange.

Having pointed out the general features 65 and aspects of my invention, I will now describe the operations in detail when a subscriber at A calls a subscriber such as A' (not shown) of the P. B. X. at which the attendant's position is located, and when the 70 attendant at F extends the connection to another P. B. X. subscriber.

When the subscriber at A removes his receiver to initiate a call a circuit is closed for the line relay 2 of the line switch C in series 75 with the line. Relay 2 operates to close a circuit for the pull down winding 3 which operates to open the springs 4 and 5 and also to close the springs 6 to 9 and 10 to 13, inclusive, to extend the line of substation A to 80 an idle selector D. As soon as springs 6 and 10 and springs 9 and 13 are closed a circuit is closed for line relay 14 of the selector D in series with the calling line. Relay 14 closes a circuit for slow release relay 15 which grounds the holding winding 16 of line switch C and prepares the circuit of vertical magnet 17 and series slow relay 18.

The calling subscriber A now operates his 90 calling device in accordance with the first digit of the called number. Relay 14 in response thereto operates magnet 17 a corresponding number of times to step the wipers to a desired level of contacts. Assuming 95 that the selector repeaters E are located in the tenth level of the selector bank then this first digit will be nought and the wipers of the selector D will be raised to the tenth level of the bank. As soon as the impulses 100 of this digit cease, relay 18 falls back to close a circuit for the rotary magnet 19 through contacts of relay 20. Magnet 19 operates to step the wipers onto the first set of contacts in this level and if this first trunk is 105 busy relay 20 will again be energized to close the circuit of magnet 19 as soon as magnet 19 closes springs 21. This alternate op-

eration of relay 20 and magnet 19 continues until an idle trunk line is reached, at which time the switching relay 22 which has hitherto been short circuited, energizes in series with the relay 20, which latter relay does not energize, and disconnects the relays of the switch D from the line circuit and connects the said line circuit to the wipers and through said wipers to the line relay of the selector repeater E (Fig. 2) to which the connection has been extended.

Line relay 23 energies in series with the extended line circuit and in turn causes the energization of slow relay 24 which operates to ground the holding circuit back to switches C and D and also to prepare the circuit of the vertical magnet 25 and slow relay 26. Relay 23 is now operated in accordance with the next digit of the called subscriber's number and in turn closes the circuit of magnet 25 and relay 26 a number of times, relay 26 remaining energized during impulses. Magnet 25 operates to step the wipers of the switch E to a desired level of the banks in which level are located trunk lines leading to the desired branch exchange. As soon as the switch steps off normal the springs 27 and 28 come into contact, springs 28 preparing the circuit of release magnet 29 and springs 27 closing a circuit for relay 30 extending from ground through springs 31 and 43, springs 35 and 36, springs 37 and 38, springs 27, and relay 30 to battery. Relay 30, upon energizing, locks itself to ground through springs 39, springs 40 and springs 27 independent of relay 26 and also prepares a circuit for the rotary magnet 41 at springs 42. As soon as relay 26 energizes it will be understood that springs 37 and 38 close contact, springs 31 and 32 open contact, springs 31, 43 and 44 close contact, and springs 45 close contact and that relay 26 remains energized as long as relay 23 vibrates in response to impulses. The closure of springs 31 and 44 of relay 26 causes relay 46 to energize to open the springs 47. Relay 48 is also energized through its lower winding and springs 31 and 44 at this time, but relays 46 and 48 have no function at this time.

A short time after the impulses for this digit cease relay 26 falls back to close the springs 37 and 49 in the circuit of magnet 41 through springs 42 of relay 30. The circuits of relays 46 and 48 and the initial energizing circuit of relay 30 are opened at springs 31 and 44 and at springs 37 and 38. Magnet 41 operates to step the wipers onto the contacts of the first trunk line in this level and also opens the holding circuit of relay 30 at springs 40. Relay 30 deenergizes and opens the circuit of magnet 41 at springs 42. Now if this first trunk line is busy a ground will be present on the test contact thereof and this ground will pass over the test wiper 54,

through springs 50 and 51, springs 52 and 53, springs 40, springs 27, and relay 30 to battery. Relay 30 will therefore energize again and close the circuit of magnet 41 at springs 42. Magnet 41 again operates and steps the wipers to the second trunk line when the testing operation is again completed and if busy the relay 30 and magnet 41 again operate. This alternate operation of relay 30 and magnet 41 continues until an idle trunk line is reached in which case there will be no ground present at wiper 54 and relay 30 will therefore not energize again to operate magnet 41. In this case a circuit is closed extending from ground through springs 31 and 32, springs 33 and 34, relay 55, to spring 53 where the circuit divides, one path extending by way of interrupter springs 40 on the rotary magnet, through off normal springs 27 and through the winding of the interrupter relay 30 to battery, and the other path extending by way of springs 53 and 52, springs 51 and 50, wiper 54, and through the cut off winding of the line switch C³ to battery. The cut off winding of the line switch C³ is energized over this circuit and attracts the cut off armature which maintains the line switch C³ inoperative. The switching relay 55 is also energized over the above circuit though the interrupter relay 30 does not operate at this time on account of the high resistance of the switching relay. The energization of relay 55 has the following results: The opening of springs 52 and 53 and of 35 and 36, and the closure of springs 52 and 35 opens the circuit of the rotary magnet, connects direct ground through springs 31 and 32, springs 33 and 34, springs 35 and 52, springs 51 and 50, and to the private wiper to hold the trunk busy and to maintain the cut off winding of the line switch C³ energized, as the original energizing circuit of the cut off winding is opened by the operation of the spring 52. The springs 56 open the circuit of the vertical magnet. The springs 57 are adjusted to close prior to the closure of springs 58 which are the last to make contact. Springs 57 operate to close a point in a bridge across the talking circuit on the called side of the condensers which is therefore in series with the line relays of the connector switch H (Fig. 4) and with the trunk line extending through the attendants trunk circuit F (Fig. 3). This circuit may be traced as follows: from battery through the upper windings of relays 59 and 60 (Fig. 4), springs of relays 61 and 62, conductor 63, springs 64 and 65 of key K, conductor 66, springs 67, springs 57, upper winding of relay 48, relay 68, springs 69 and 70, springs 71 and 72, springs 73 of line relay 23, springs 74 and 75, wiper 77, conductor 78, springs 79 and 80 of key K, conductor 81, springs of relays 62 and 61, and lower windings of

relays 60 and 59 in series to ground. Relays 59 and 68 operate over this circuit, relay 60 being differentially wound does not operate at this time. Relay 68 upon energizing, 5 closes springs 82 to hold relay 46 operated, relay 46 preventing relays 83 and 84 from operating at this time. Relay 48 is an electro-polarized relay and its windings in this case have current flowing in such directions 10 as to oppose each other so that the relay does not energize at this time. It will therefore be seen that when the trunk line is seized and relay 55 energizes, the relay 68 is first to energize to close the circuits of relays 46 15 and 48 before the springs 58 of relay 55 close the circuit of relay 83 and the circuit of relay 83 is therefore held open at springs 47. The relay 59 of the connector H is held energized in series with the trunk circuit 20 and with relay 68 and operates to close the circuit of relay 85 which also operates to prepare the circuit of vertical magnet 86 and slow relay 87 and grounds the release trunk to make the trunk busy at its normals 25 and to light the signal lamp 88 (Fig. 3) to notify the attendant that the switch has been seized, and also operates the visual signal 89 before the operator to show that the trunk is busy. The circuit of relay 85 extends 30 from ground through resistance 90, (Fig. 2) springs of key K², conductor 91, springs 92 and 93, and through relay 85 to battery. This resistance 90 is high enough to prevent the magnets of the switch H 35 from operating but allows relay 85 to operate.

When the operator sees the lamp 88 lighted she throws the calling device and listening key K' which connects her head 40 set across the cord circuit and also connects the calling device C. D. in series with the dialing conductor 94 which leads to the relay 87 and magnet 86.

As soon as the operator learns the wanted 45 number she operates the calling device C. D. to interrupt the circuit of magnet 86 and relay 87 a number of times through circuit extending from ground through springs 95 and 96, dial off normal springs 97, interrupter springs 98, springs 99, dial conductor 94, springs 100 of relay 82 which is held energized, off normal springs 101 and 102, and magnet 86 and relay 87 to battery. Magnet 86 operates to step the wipers to the desired 50 level, relay 87 remains energized during impulses to hold a new circuit for itself and magnet 86 after the off normal springs operate and as soon as impulses cease relay 87 on falling back prepares a circuit for slow 55 relay 103 and rotary magnet 104. When the calling device is operated for the next digit the impulses pass from the conductor 94, through springs 100, springs 101 and 105, springs 106 and 107, relay 103, springs 60 108, springs 109 and 110, and magnet 104 to 65 battery. Magnet 104 operates over this circuit to step the wipers of the switch H to the contacts in the selected level to which is connected the wanted subscriber's line. Relay 103 remains energized during impulses to 70 hold the circuit of relay 111 closed and for a short time after impulses cease. Relay 111 opens the springs 108 which are short circuited by the springs of relay 103 during energization of relay 103, opens the circuit of 75 relay 112, and prepares a circuit for its own upper winding to the private wiper 113. Certain of the subscribers' lines accessible to this connector are grounded so that if one of the lines are busy the switch will rotate on 80 to the next line of the group. The private contacts of single lines and of the last contacts of a group are not connected together while all but the last pair of private contacts of a group are connected together. Now if 85 the switch is operated too the first set of contacts of a group and this contact is busy, then ground will be connected to both test wipers 113 and 114 and relay 111 will be held energized through its upper winding, 90 while relay 119 will also be energized from ground on wiper 114, through springs 116 of relay 103 after that relay falls back, springs 117, springs 118 and relay 119 to battery. Relay 119 operates to close a holding circuit 95 for itself through springs 120 and connects ground through springs of relay 85, through springs 121, springs 109 and 110, and magnet 104 to battery. Magnet 104 operates to step the wipers to the next 100 set of contacts and opens the circuit of relay 119. If the next trunk is busy the same operation occurs until the wipers reach the last contacts of a group which are like a single line and are not connected together. If this line is busy relay 111 will alone be held energized to give the busy 105 signal but relay 119 will not energize. As soon as the line becomes idle or if it is idle at first then after an interval relay 111 will 110 fall back and a circuit is completed for the cut on relay 112 which energizes through its upper winding and locks through its lower winding to connect the trunk through to the wipers and open the circuits of the magnets. 115 The called party is now signalled by means of the ringing equipment R and when the called party answers the relay 122 is energized to cut off the ring and to connect the called line to the back bridge relay 61. 120 When relay 61 energizes, the signal lamp 123 at the attendant's trunk is lighted to inform the operator that the called man has answered. Conversation may proceed in the usual manner with the switch H held up by line relay 59 which is energized over two 125 sides of the trunk circuit in series. It may be here pointed out that if the operator so desires the key K² may be thrown by the operator to put direct ground on the springs 130 135

of the line relay of switch H to permit calls to be completed by the calling party in the main exchange without the intervention of the attendant.

Assuming that the operator has the key K⁴ thrown when the selector repeater E, Fig. 2, establishes connection with the trunk line comprising conductors 66 and 78, the calling subscriber may be operating his calling device in accordance with the two digits of the number of the desired subscriber in the branch exchange establish his own connection. In response to the operation of the calling device the line relay 23 of the selector repeater E repeats the impulses over the trunk line to the line relay 59 of the connector H by way of spring 73. It will be remembered that the original energizing circuit of relay 59 was completed by way of spring 73 but that the connector switch H could not be operated by the calling subscriber as the conductor 91 was not connected to ground direct. However, as the conductor 91 is now connected to direct ground the connector H will operate under the control of its line relay 59 to complete the desired connection in the usual manner.

Now let us assume that the branch exchange which is handled through the attendant's trunk F (Fig. 3) is in the office or factory of a concern who also have another private branch exchange located in their warehouse or other branch which is accessible to another level of the selector repeaters E in the main exchange or to other selector repeaters in said main exchange. Now if the calling party desires to speak to some party who at the time of calling is known to be at the other branch exchange then when the attendant at F receives the calling party's order for this party or his number I have provided means which I will now explain for enabling the attendant at E to extend the call to the other or another branch exchange from the selector repeater E in the main exchange without having to inform the calling party to hang up and call another number.

When the attendant finds that a party in some other branch exchange is wanted she will restore key K' and then throw her "call out" key K which will cause the trunk circuit to pass from conductor 66 through springs 125 of key K², springs 65 and 127, through the resistance of the coils in the operator's head set, springs 98 of calling device C. D., springs 129 and 79, springs 130 of key K² and conductor 78.

The operation of this key to change the circuit of the bridged relays 68 and 48, only relay 68 of which is energized, causes relay 68 to fall back to open the circuit of slow relay 46 which has heretofore prevented relay 83 from energizing. As soon as springs 47 of relay 46 close relay 83 energizes and

locks energized with the following result, the circuit including the calling device of the attendant's circuit is now connected from conductor 66, through wiper 76, springs 131 and 132, springs 57, upper winding of relay 48, relay 68, springs 69 and 70, springs 71 and 134, and conductor 135 to the line switch C'. The other side of the circuit extends from conductor 78, through wiper 77, springs 136, springs 74 and 137 and to conductor 138 extending to line switch C'.

Now as soon as the above traced circuit including the line relay of line switch C', the relays 48 and 68 and the springs 98 and 97 of the calling device is completed the line switch C' operates to automatically select an idle selector switch such as D (Fig. 1) and as the dial is operated in accordance with the number of the wanted branch exchange or wanted subscriber the seized selector will be operated as was the selector D to seize a selector repeater such as E and to extend the connection to the desired subscriber. I have not shown this equipment in the main exchange through the medium of which the call is extended as it will be understood that this apparatus might be simply a selector and connector of the well known type or might very likely be simply a duplicate of the switches shown at D and E. Now when the wanted subscriber answers the battery will be reversed over the extended connection and back over the series circuit including relays 48 and 68 in the selector repeater E (Fig. 2). When the battery is thus reversed in the upper winding of relay 48, said relay energizes due to both its windings assisting each other and acts to close the circuit of relay 84 at springs 140, and closes the circuit of reversing relay 141 at springs 142 and 143. Relay 141 energizes to reverse the battery back to the calling line.

Relay 84 locks energized to ground through springs 144, opens the springs 136 in the series circuit extending to the attendant's trunk circuit, removes ground from the private wiper 54 to allow the trunk to the private branch to be used for other calls, opens the springs 131 and 132 to complete the cutting off of the trunk to the branch exchange, opens the initial circuit of relays 48 and 68 at springs 70 and 69 and completes a holding bridge for the extended connection which extends from conductor 135 of switch C' through springs 133 and 132, springs 57, upper winding of relay 48, relay 68, springs 69 and 145, springs 73, springs 74 and 137, and conductor 138.

It will be seen therefore, that the calling subscriber may now converse with the wanted party in the second exchange and that the trunk to the first called exchange attendant is free and may be used for calls to that exchange from some other selector repeater into which it is multipled or for

calls from the branch exchange to the main exchange, in which case the line switch C³ is used to complete the call in the main exchange. I have accomplished this result in 5 a very simple manner through the medium of an improved selector repeater E, an attendant's trunk circuit which is of a very simple design consisting of keys and signals without any relays, and a rotary connector 10 which is adapted for this type of private branch exchange work.

Having described and pointed out the features and aspects of my invention, what I consider to be new and desire to have protected by Letters Patent will be pointed out 15 in the appended claims.

What I claim as my invention is:

1. In a telephone system, a directly controlled automatic switch, lines accessible thereto, a variable impulse sender common to said lines, an automatic non-numerical switch individual to said switch, means for operating said first switch to extend a connection to one of said lines, other automatic 25 switches, means controlled over the called line exclusive of the said impulse sender for operating said non-numerical switch to extend the connection to one of said other automatic switches, and means controlled 30 by said impulse sender for operating the seized automatic switch to extend the connection in the direction of another called line.

2. In a semi-automatic telephone system, 35 an operator's trunk circuit, a directly controlled switch for extending a connection to said circuit, another automatic switch individual to said first switch, a calling device associated with said trunk circuit, operator's equipment separate from said calling device for operating said second switch in the direction of a called line, and another switch responsive to said calling device to complete the connection to the called line.

45 3. In a telephone system, an automatic switch, lines accessible thereto, an automatic non-numerical switch individual to said switch, means for operating said first switch to extend a connection to one of said lines, means controlled by the subscriber on the called line for operating said non-numerical switch to extend the connection to another called line, and means controlled by the subscriber on the second called line for 50 opening the first extended connection.

4. In a telephone system, an automatic switch, a trunk line accessible to said switch terminating in another automatic switch, operator's equipment in said trunk line, means for operating said first switch to seize said trunk line, and signal the operator, and to 55 then operate the other automatic switch to extend the connection to a called line, means controlled by the operator for preventing the operation of said other switch and for

connecting a calling device with said trunk line to either operate said other switch directly or to break the connection to said other switch and extend the connection from said first switch to a third automatic switch. 70

5. In a telephone system, an automatic switch, a trunk line accessible to said switch terminating in another automatic switch, operator's equipment in said trunk line, means for operating said first switch to seize said 75 trunk line and signal the operator, and to then operate the other automatic switch to extend the connection to a called line, means controlled by the operator for preventing the operation of said other switch and for 80 connecting a calling device with said trunk line to either operate said other switch directly or to break the connection to said other switch and extend the connection from said first switch to another automatic switch, 85 and means controlled from said last automatic switch for breaking the connection from said first switch to said trunk line.

6. In a telephone system, an automatic switch, trunk lines accessible thereto, another switch associated therewith normally disconnected therefrom, means for operating said first switch to seize one of said trunk lines, means controlled by the opening of the conductors of the seized trunk line for connecting said other switch with said first switch and means controlled by the initial closure of the conductors of said trunk line for operating said other switch to extend a 90 connection from the first switch. 95

7. In a telephone system, an automatic switch, trunk lines accessible thereto, another automatic switch associated therewith normally disconnected therefrom, means for operating said first switch to seize one of said trunk lines, means controlled by the opening of the conductors of the seized trunk line for connecting said other switch with said first switch and means controlled by the initial closure of the conductors of said trunk line for operating said other switch to extend a connection from the first switch and excluding said seized trunk line. 105 110

8. In a telephone system, an automatic switch, trunk lines accessible thereto, another switch individual thereto normally disconnected therefrom, means for operating said first switch to seize one of said trunk lines, means controlled by the opening of the conductors of the seized trunk line for connecting said other switch with said first switch and means controlled by the initial closure of the conductors of said trunk line for operating said other switch to extend a connection from the first switch. 115 120

9. In a telephone system, an automatic switch, trunk lines accessible thereto, another automatic switch associated therewith normally disconnected therefrom, means for operating said first switch to automatically 125 130

selection idle one of said trunk lines, means controlled by the opening of the conductors of the seized trunk line for connecting said other switch with said first switch and means controlled by the initial closure of the conductors of said trunk line for operating said other switch to extend a connection from the first switch.

10. In a telephone system, an automatic switch, a non-numerical switch individual thereto but normally disconnected therefrom, trunk lines accessible to said switches, means for operating said automatic switch to seize one of said trunk lines, a calling device associated with said seized trunk line, operator's equipment separate from said calling device associated with said seized trunk line, for causing the connection of said non-numerical and automatic switches and for operating said non-numerical switch to extend a connection to another one of said trunk lines, and another switch responsive to said calling device to complete the connection to a called line.

11. In a telephone system, a trunk line, an automatic switch for extending connections from said trunk line to any one of a plurality of other trunk lines which are accessible to said switch, another automatic switch individual to said first trunk line, another line, means for operating said first switch to extend a connection to one of said other trunk lines, means controlled over the extended connection and said last mentioned trunk line responsive to a single closure of a metallic circuit across the trunk line for operating said second switch to automatically extend a connection to said other line.

12. In a telephone system, an automatic switch, a non-numerical switch individual thereto but normally disconnected therefrom, trunk lines accessible to said switches, means for operating said automatic switch to seize a trunk line, means controlled over the seized trunk line for connecting the non-numerical to the automatic switch and for operating the non-numerical switch to extend a connection to another one of said trunk lines, and means controlled over the last mentioned connection for breaking the connection of said first automatic switch to the seized trunk line.

13. In a telephone system, an operator's position, an automatic switch, trunk lines accessible to said switch terminating in a connector switch, means for causing said automatic switch to select an idle one of said trunk lines and then repeat impulses over it to operate said connector switch to complete a connection to a called line, means controlled from said operator's position to prevent the operation of said connector switch, a nonnumerical switch individual to said automatic switch, means controlled from the said operator's position over the

selected trunk line to cause said non-numerical switch to operate to extend the connection to another called line.

14. In a telephone system, an automatic switch, a nonnumerical automatic switch individual thereto, trunk lines accessible to said automatic switch, an operator's position, a signal thereat, means for operating said automatic switch to select an idle one of said trunk lines and operate said signal, means at the operator's position to complete the connection to a called subscriber's line or to operate said individual switch over the selected trunk to extend the call to a second called subscriber's line.

15. In a telephone system, an automatic switch, a nonnumerical automatic switch individual thereto, trunk lines accessible to said automatic switch, an operator's position, a signal thereat, means for operating said automatic switch to select an idle one of said trunk lines and operate said signal, means at the operator's position to complete the connection to a called subscriber's line over the said trunk line, or to operate said individual switch over the selected trunk to extend the call to a second called subscriber's line.

16. In a telephone system, an automatic switch, a nonnumerical automatic switch individual thereto, trunk lines accessible to said automatic switch, an operator's position, a signal thereat, means for operating said automatic switch to select an idle one of said trunk lines and operate said signal, means at the operator's position to complete the connection to a called line, or to operate said individual switch over a circuit including the selected trunk to extend the call to a second called line.

17. In a telephone system, a subscriber's line, an automatic switch, a nonnumerical switch individual thereto, trunk lines accessible to said automatic switch, means for extending said line to said automatic switch, an operator's position and a signal thereat, means for operating said automatic switch to select an idle one of said trunk lines and operate said signal, said automatic switch operating thereafter to repeat impulses over the selected trunk to complete a connection to a called line, and means at the operator's position for preventing said last named operation and for operating said nonnumerical switch over the selected trunk to complete a connection to a second called line.

18. In a semi-automatic telephone system, an operator's trunk circuit, a switch for extending a connection to said trunk circuit, another switch associated with said first switch, means controlled by the operator at the trunk circuit for operating said other switch to extend a connection to a called subscriber, and means controlled by the response of the called subscriber independent of said trunk circuit for opening the first

extended connection to said trunk circuit.

19. In a telephone system, a main exchange, a plurality of branch exchanges, an automatic switch in said main exchange, 5 trunk lines accessible to said automatic switch extending to said branch exchange, an automatic non-numerical switch associated with said first switch, means for operating said first switch to connect with a trunk line 10 extending to one of said branch exchanges, and means controlled over said trunk including said non-numerical switch to extend a connection to another of said branch exchanges over another one of said trunk lines.
15. 20. In a telephone system, an automatic switch, telephone lines divided into groups 15 accessible thereto, means for operating said switch vertically in order to select one of said groups and for then rotating said switch 20 into connection with one of said lines, a test wiper for said switch, a slow acting test relay for said switch, another slow acting relay energized during the rotary movement of said switch, a circuit for said test relay completed 25 by said other relay, and a second circuit for said test relay including said test wiper.

21. In a telephone system, an automatic switch, telephone lines accessible thereto 30 divided in groups and sub-groups, said switch having a directly controlled movement to select groups and subgroups and an automatic movement to select an idle line in the selected subgroup, a relay energized only 35 during the movement of said switch in selecting subgroups, a test wiper for said switch, a slow acting test relay for said switch, a circuit for said test relay closed by the first mentioned relay, and a locking circuit for 40 said test relay including said test wiper.

22. In a telephone system, telephone lines, a first exchange and a second exchange, a trunk line interconnecting said exchanges and terminating at said second exchange in 45 an automatic switch, an automatic switch in said first exchange having access to said trunk line, a non-numerical switch individual to the second mentioned automatic switch, a third exchange, trunk lines accessible 50 to said non-numerical switch extending said third exchange, means controlled from a calling one of said telephone lines in said first exchange for operating said second switch to seize the first mentioned trunk line, means controlled from 55 said calling line for then operating the first mentioned switch, means then operative controlled over said first trunk line for operating said non-numerical switch to connect with one of said other trunk lines, and an automatic switch in said third exchange controlled 60 over the connected trunk line to complete the connection to one of said telephone lines in said third exchange.

23. In a telephone system, telephone lines, 65 a first exchange and a second exchange, a trunk line interconnecting said exchanges and terminating at said second exchange in an automatic switch, an automatic switch in said first exchange having access to said 70 trunk line, a non-numerical switch individual to the second mentioned automatic switch, a third exchange, trunk lines accessible to said non-numerical switch extending to said third exchange, means controlled from a 75 calling one of said telephone lines in said first exchange for operating said second switch to seize the first mentioned trunk line, means controlled from said calling line for then operating the first mentioned switch, 80 means then operative controlled over said first trunk line for operating said non-numerical switch to connect with one of said other trunk lines, an automatic switch in said third exchange controlled over the connected 85 trunk line to complete the connection to one of said telephone lines in said third exchange, and means for disconnecting said first trunk line from the connection.

24. In a telephone system, a first exchange 90 and a second exchange, a trunk line interconnecting said exchanges, a directly controlled automatic switch having access to said trunk line in said first exchange, an automatic non-numerical switch associated with 95 said trunk line in said first exchange, a non-numerical switch individual to said directly controlled switch, a group of trunk lines accessible to said non-numerical switches, means controlled over the first mentioned 100 trunk line for operating said associated non-numerical switch to seize a trunk line in said group, means for operating said directly controlled switch to connect with said first trunk line, and means operative when said 105 directly controlled switch is in connection with said first trunk line for preventing the operation of said associated non-numerical switch and for operating said individual non-numerical switch. 110

25. In a telephone system, a first exchange and a second exchange, a trunk line interconnecting said exchanges, a directly controlled automatic switch having access to said trunk line in said first exchange, an automatic non-numerical switch associated with 115 said trunk line in said first exchange, another automatic non-numerical switch individual to said directly controlled switch, a group of trunk lines accessible to said non-numerical switches, said directly controlled switch being operable to connect with the first mentioned trunk line, and means controlled over said first trunk line for operating said associated non-numerical 120 switch to seize a trunk line in said group or if said directly controlled switch has connected with the said first trunk line for pre- 125

venting the operation of said associated non-numerical switch and for operating said individual switch to seize a trunk line in said group.

- 5 26. In a telephone system, a first exchange and a second exchange, a trunk line interconnecting said exchanges, a directively controlled automatic switch having access to said trunk line in said first exchange, an 10 automatic non-numerical switch associated with said trunk line in said first exchange, another automatic non-numerical switch individual to said directively controlled switch, a group of trunk lines accessible to 15 said non-numerical switches, said directively controlled switch being operable to connect with the first mentioned trunk line, means controlled over said first trunk line for operating said associated non-numerical 20 switch to seize a trunk line in said group or if said directively controlled switch has connected with the said first trunk line for operating said individual non-numerical switch to seize a trunk line in said group.
- 25 27. In a telephone system, an automatic switch, trunk lines accessible to said switch terminating in other automatic switches, means for operating said first mentioned switch to select an idle one of said trunk lines and repeat impulses thereover to operate a said other switch to complete a connection to a called subscriber's line, another switch, and means controlled over the select-

switch associated with said first mentioned 35 trunk line for operating said associated switch to extend a connection to a second called subscriber's line before said other switch is operated.

28. In a semiautomatic telephone system, a calling line, an operator's trunk circuit, a 40 switch directively controlled from said calling line for extending a connection to said circuit, another automatic switch individual to said first switch, means controlled by the operator for operating said other switch to 45 extend the connection from said first switch to a called subscriber, and means controlled by the called subscriber for opening the first connection to the operator's trunk circuit.

29. In a telephone system, an automatic 50 switch, trunk lines accessible to said switch, means for operating said switch to select an idle one of said trunk lines and to repeat impulses thereover, another switch associated with said first switch, means controlled over said selected trunk line for operating said other switch to extend a connection from the first switch to a called line, and means controlled from the called line exclusive of control over said selected trunk 55 line to break the connection from the first switch to the selected trunk line.

Signed by me at New York, N. Y., this 7th day of March, 1919.

EMIL JACOBSEN.
